CLAIM

The ornamental design for an alphabet curtain rod, as shown and described.

DESCRIPTION

FIG. 1 is a perspective showing my new design for an alphabet curtain rod;

FIG. 2 is a front elevational view thereof on an enlarged scale with the central rod broken to illustrate variable length between the finial portions thereof;

FIG. 3 is a rear elevational view thereof;

FIG. 4 is a top plan view thereof, the bottom plan view being identical thereto;

FIG. 5 is a right side elevational view, the left side elevational view being identical thereto;

FIG. 6 is a front elevational view of the finial portion removed from the rod;

FIG. 7 is a rear elevational view thereof;

FIG. 8 is a top plan view, the bottom view being identical thereto;

FIG. 9 is a left side elevational view thereof;

FIG. 10 is a right side elevational view thereof;

FIG. 11 is a front elevational view of a modified form of the alphabet curtain rod shown in FIG. 2;

FIG. 12 is a rear elevational view thereof;

FIG. 13 is a top plan view thereof, the bottom plan view being identical thereto;

FIG. 14 is a right side elevational view, the left side elevational view being identical thereto;

FIG. 15 is a front elevational view of the finial portion removed from the rod;

FIG. 16 is a rear elevational view thereof;

FIG. 17 is a top plan view thereof;

FIG. 18 is a left side elevational view thereof; and,

FIG. 19 is a right side elevational view thereof.

The finial portion of the curtain rod has been shown detached for clarity of illustration.

The broken line showing of a frame, support arms and curtains in FIG. 1 is for illustrative purposes and forms no part of the claimed design.
